US0D1084303S

(12) **United States Design Patent** (10) Patent No.: **US D1,084,303 S**
(45) Date of Patent: ** Jul. 15, 2025

(54) **INTERMITTENT URINARY CATHETER**

(71) Applicant: **Hollister Incorporated**, Libertyville, IL (US)

(72) Inventors: **Satwinder S. Panesar**, Foxford (IE); **David F. Pierce**, Ballina (IE); **David J. Farrell**, Ballina (IE); **Rory O'Brien**, Galway (IE); **Keith Dwyer**, Ballina (IE)

(73) Assignee: **Hollister Incorporated**, Libertyville, IL (US)

(**) Term: **15 Years**

(21) Appl. No.: **29/878,289**

(22) Filed: **Jun. 20, 2023**

(30) **Foreign Application Priority Data**

CLAIM

The ornamental design for an intermittent urinary catheter as shown and described.

DESCRIPTION

FIG. 1 is a perspective view of the intermittent urinary catheter;

FIG. 2 is a front elevational view of the intermittent urinary catheter;

FIG. 3 is a rear elevational view of the intermittent urinary catheter;

FIG. 4 is a left side elevational view of the intermittent urinary catheter;

FIG. 5 is a right side elevational view of the intermittent urinary catheter;

FIG. 6 is a top plan view of the intermittent urinary catheter; and

FIG. 7 is a bottom plan view of the intermittent urinary catheter.

FIG. 8 is a perspective view of a second embodiment of the intermittent urinary catheter of our new design;

FIG. 9 is a front elevational view of the intermittent urinary catheter;

FIG. 10 is a rear elevational view of the intermittent urinary catheter;

FIG. 11 is a left side elevational view of the intermittent urinary catheter;

FIG. 12 is a right side elevational view of the intermittent urinary catheter;

FIG. 13 is a top plan view of the intermittent urinary catheter; and

FIG. 14 is a bottom plan view of the intermittent urinary catheter.

FIG. 15 is a perspective view of a third embodiment of the intermittent urinary catheter of our new design;

FIG. 16 is a front elevational view of the intermittent urinary catheter;

FIG. 17 is a rear elevational view of the intermittent urinary catheter;

FIG. 18 is a left side elevational view of the intermittent urinary catheter;

FIG. 19 is a right side elevational view of the intermittent urinary catheter;

FIG. 20 is a top plan view of the intermittent urinary catheter; and

FIG. 21 is a bottom plan view of the intermittent urinary catheter.

FIG. 22 is a perspective view of a fourth embodiment of the intermittent urinary catheter of our new design;

FIG. 23 is a front elevational view of the intermittent urinary catheter;

FIG. 24 is a rear elevational view of the intermittent urinary catheter;

FIG. 25 is a left side elevational view of the intermittent urinary catheter;

FIG. 26 is a right side elevational view of the intermittent urinary catheter;

FIG. 27 is a top plan view of the intermittent urinary catheter; and

FIG. 28 is a bottom plan view of the intermittent urinary catheter.

FIG. 29 is a perspective view of a fifth embodiment of the intermittent urinary catheter of our new design;

FIG. 30 is a front elevational view of the intermittent urinary catheter;

FIG. 31 is a rear elevational view of the intermittent urinary catheter;

FIG. 32 is a left side elevational view of the intermittent urinary catheter;

FIG. 33 is a right side elevational view of the intermittent urinary catheter;

FIG. 34 is a top plan view of the intermittent urinary catheter; and

FIG. 35 is a bottom plan view of the intermittent urinary catheter.

FIG. 36 is a perspective view of a sixth embodiment of the intermittent urinary catheter of our new design;

FIG. 37 is a front elevational view of the intermittent urinary catheter;

FIG. 38 is a rear elevational view of the intermittent urinary catheter;

FIG. 39 is a left side elevational view of the intermittent urinary catheter;

FIG. 40 is a right side elevational view of the intermittent urinary catheter;

FIG. 41 is a top plan view of the intermittent urinary catheter; and

FIG. 42 is a bottom plan view of the intermittent urinary catheter.

FIG. 43 is a perspective view of a seventh embodiment of the intermittent urinary catheter of our new design;

FIG. 44 is a front elevational view of the intermittent urinary catheter;

FIG. 45 is a rear elevational view of the intermittent urinary catheter;

FIG. 46 is a left side elevational view of the intermittent urinary catheter;

FIG. 47 is a right side elevational view of the intermittent urinary catheter;

FIG. 48 is a top plan view of the intermittent urinary catheter; and

FIG. 49 is a bottom plan view of the intermittent urinary catheter.

FIG. 50 is a perspective view of an eighth embodiment of the intermittent urinary catheter of our new design;

FIG. 51 is a front elevational view of the intermittent urinary catheter;

FIG. 52 is a rear elevational view of the intermittent urinary catheter;

FIG. 53 is a left side elevational view of the intermittent urinary catheter;

FIG. 54 is a right side elevational view of the intermittent urinary catheter;

FIG. 55 is a top plan view of the intermittent urinary catheter; and

FIG. 56 is a bottom plan view of the intermittent urinary catheter.

The break lines indicate that the appearance of any portion of the intermittent urinary catheter between the break lines forms no part of the claimed design.
